Filed Oct. 6, 1958, Ser. No. 52,871

Term of patent 14 years

(Cl. D52—2)

FIG. 1

FIG. 3

FIG. 2

FIG. 4

FIG. 1 is a front elevation of a gasoline pump service station unit with the overhead supporting column shown broken away to indicate indeterminate length embodying my new design.

FIG. 2 is a side elevational view thereof with the column portion broken away for convenience of illustration.

FIG. 3 is a top plan view thereof with the column shown in horizontal cross-section.

FIG. 4 is a fragmentary vertical sectional view, taken on the line 4—4 in FIG. 3.

The rear of the gasoline pump is substantially the same

in appearance as the front, and the undisclosed side is the same in appearance as the side shown.

I claim:

The ornamental design for a gasoline pump service station unit, as shown and described.
